US0D1062692S

(12) **United States Design Patent** (10) Patent No.: **US D1,062,692 S**
(45) Date of Patent: ** Feb. 18, 2025

(54) **HEADSET**

(71) Applicant: **Cisco Technology, Inc.**, San Jose, CA (US)

(72) Inventors: **Naoki Shimada**, Sunnyvale, CA (US); **Otto Williams**, Berkeley, CA (US)

(73) Assignee: **Cisco Technology, Inc.**, San Jose, CA (US)

(**) Term: **15 Years**

(21) Appl. No.: **29/942,228**

(22) Filed: **May 14, 2024**

Related U.S. Application Data

(63) Continuation of application No. 29/866,824, filed on Sep. 28, 2022, now Pat. No. Des. 1,035,614.

CLAIM

The ornamental design for a headset, as shown and described.

DESCRIPTION

FIG. 1 is a top, front, right-side perspective view of a headset;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the headset that form no part of the claimed design.

1 Claim, 8 Drawing Sheets
